UNITED STATES PATENT OFFICE.

WILLIAM AMENDA, OF ST. LOUIS, MISSOURI.

COMBINED REFRIGERATOR, SHOW-CASE, AND COUNTER.

1,168,776.

Specification of Letters Patent. Patented Jan. 18, 1916.

Application filed August 19, 1912. Serial No. 715,811.

To all whom it may concern:

Be it known that I, WILLIAM AMENDA, a citizen of the United States of America, residing in the city of St. Louis and State of Missouri, have invented certain new and useful Improvements in Combined Refrigerators, Show-Cases, and Counters, of which the following is a specification.

The primary object of this invention is in 10 providing improved refrigerating means in a dining counter whereby the ready for serving eatables are protected from exposure, and at the same time are exposed to the view of customers.

15 Another object is to provide improved refrigerating means to a show case or counter, whereby perishable foods can be preserved, and at the same time are visible for the inspection of prospective customers.

20 A further object is in providing an improved refrigerator show case and serving counter, so that perishable eatables can be kept therein in cooled compartments being in sight and adjacent to the customers and 25 servers, so that quick and efficient service can be given.

A still further object is in providing improved air circulating means to this improved combined refrigerator show case and 30 counter.

Other and further objects will appear in the specification and be specifically pointed out in the appended claims, reference being had to the accompanying drawings exemplifying the invention, and in which—

Figure 1 is a vertical longitudinal section through this improved combined show case and counter taken on the line I—I of Fig. 2. Fig. 2 is a plan view of Fig. 1, partly in section and taken on the line II—II of Fig. 1.

40 Fig. 3 is an enlarged vertical section taken on the line III—III of Fig. 1. Fig. 4 is an enlarged vertical section taken on the line IV—IV of Fig. 1. Fig. 5 is an enlarged vertical section taken on the line V—V of Fig. 1. Fig. 6 is an enlarged vertical section taken on the line VI—VI of Fig. 1. Fig. 7 is an enlarged vertical section taken on the line VII—VII of Fig. 1. Fig. 8 is an 45 enlarged fragmentary sectional plan of a portion of the upper cooling compartment.

50 Fig. 9 is a vertical section through a show-case showing the improved cooling compartments mounted therein.

55 Referring to the drawings, the box portion 1 of this show case counter has mounted

thereon the show case 2, and in the center portion of the box portion 1 is formed a refrigerating compartment 3; formed on each side of the refrigerator compartment are a 60 series of cooling compartments 4. Formed adjacent the ends of the box portion 1 are drawers 5 and shelves 6.

In the construction of this improved show case and counter the rear wall 7, front wall 8, bottom 9, and ends 10, are preferably constructed of wood, and have an insulation 11 incased therein. The show case 2, being mounted on the box portion 1 of the counter, has an extended portion 12, which extends 65 beyond the front wall 8 of the box portion 1. The front portion 13, of the top surface of the show case 2, is preferably constructed of wood, and is insulated. Whereas the rear and center portion of the show case top is 70 constructed of glass, there being 2 glass layers 14, spaced apart forming a chamber 15. The front and ends of the show case 2, are also constructed of glass, the glass layers 16, being spaced apart forming a chamber 75 17. Mounted in the refrigerator compartment 3, adjacent the front wall 8, and on the supporting rods 18, are liquid containers 19; said liquid containers being for the purpose of containing different kinds of drinks, and 80 leading from the bottom of said containers are the draw-off pipes 20, which are controlled by the faucets 21. Mounted in a drip pan 22, beneath the containers 19, is a coil of pipe 23, which is for the purpose of 85 having water circulate therethrough; said coil 23, receiving its supply from the supply pipe 24, and discharging out of a discharge pipe 25, which will be controlled by a faucet “not shown” similar to and in alignment 90 with the faucet 21, which is at the rear of the counter. Connecting with the drip pan 22, is a drain pipe 26, having the usual water trap 27 connected thereto. Mounted adjacent the top of the water coil 23, is an ice 95 rack or support 28, so that when a block of ice is placed thereon, and the water coil being adjacent the water in said coil will be sufficiently cool for drinking purposes; and by the position of the liquid containers in relation to the ice the liquids contained therein 100 will be kept cool.

Formed in the rear wall 7, adjacent the ice rack 28, is a door 29, and formed in said wall 7 adjacent the lower end of the refrigerating compartment 3, is a door 30. Formed on each side of the refrigerating 110

compartment 3, are a series of vertical air passage ways 31—32 and 33 respectively; said passage ways receiving communication from the refrigerator compartment 3, through the horizontal passage ways 34. These vertical air passage ways 31—32 and 33, are for the purpose of conveying cool air to the respective compartments to be cooled; the cool air upon traveling up the vertical passage ways 33, will pass through the openings 36, formed in the bottom of the show case compartment 2, and will enter the horizontal passage ways 37, and will travel on to the ends of the show case until the openings 38 are reached, then the air will travel the passage ways 39 on to the openings 40, formed in the center of the bottom of the show case 2, through which the air will pass and enter the refrigerated compartment 3, down the passage way 64.

In forming the horizontal passage ways 37 and 39, it is preferable to use inverted channel members 41, which extend longitudinal of the show case 2, to the points adjacent the ends of said show case. Formed on one side of these inverted channel members 41, adjacent the horizontal passage ways 39, are a series of openings 42, said openings being for the purpose of allowing air to be drawn in to the inverted channel members. This will increase the speed of the air currents as the air is discharged through the opening 40.

Mounted on the bottom of the show case 2, adjacent the walls thereof are resting strips 43, said resting strips along with the inverted channel members 41, serving as supports for trays 44, said trays being preferably made of enameled metal or glass, and when mounted in place form the top of the horizontal passage ways 37 and 39; and at the same time are for the purpose of containing food stuffs.

In order to get the air to the upper compartments 4, the air after entering the horizontal passage ways 34, will traverse the vertical passage ways 32, and will enter the short horizontal passage ways 45, which horizontal passage ways 45 pass through the vertical passage ways 33, and connect with the horizontal passage ways 46; located in the upper compartments 4. After the air has traversed the horizontal passage ways 46, the air will pass into the return horizontal passage ways 47, through the openings 48, and will then pass on out and up through the vertical passage ways 49; and will return to the top of the refrigerator compartments 3, through the discharge openings 50.

In getting the air to the middle compartments 4, the air will enter the vertical passage ways 31 from the horizontal passage ways 34, and will then cross through the vertical passage ways 32 and 33 by way of

the horizontal passage ways 51; and will enter horizontal passage ways 52, and traverse the length of the middle compartments 4, and will return on through the openings 53 and horizontal passage ways 70 54, and after the air has traversed these horizontal passage ways it will be returned to the top of the refrigerator compartment 3 through the vertical passage ways 49, and opening 50. In getting the air to the lower compartments 4, the air will pass along the horizontal passage ways 34 and enter the horizontal passage ways 55; in the lower compartments 4 through the openings 56, and after traversing the length of said lower compartments 4, the air will pass through the openings 56^a at the ends of said compartments and will be returned to the vertical passage ways 49 through the horizontal passage ways 57; and the air after traversing said vertical passage ways 49 will enter the top of the refrigerator compartment 3, through the openings 50.

In forming the horizontal passage ways 46—47—52—54—55—57 inverted channel members 58 are used, said inverted channel members 58 being constructed similar to the inverted channel members 41; in the compartments 4 are resting strips 59, which along with the inverted channel members 58 serve as supports for trays 60.

In order to have access to the show case 2, doors such as 61 are formed in the rear wall 7 of the counter adjacent the show case and doors such as 62 are also formed in the rear of wall 7 in order to have access to the compartments 4.

In the chambers 15 and 17 formed by the spaced layers of glass 14 and 16 a vacuum is produced, which acts as an insulation to the transparent portion of the show case 2, and will also prevent vapor forming on the transparent surfaces; so that customers can see through said transparent surface and inspect food stuffs in said show case.

In the operation of this improved device assuming that the shelving 28 is laden with ice the refrigerator compartment 3 will become cool and the ice being adjacent the water coil 23 and the liquid containers 19 will cool the contents therein.

It is a well known fact that the cold air will descend and in so doing the air will enter the horizontal passage ways 34, said horizontal passage ways being adjacent the bottom of the refrigerator compartment 3 and will enter the compartments to be cooled through their respective vertical passage ways 31—32 and 33, and as afore described after circulating through the compartments, will be returned back to the top of the refrigerator by reason of the air becoming gradually warmer; then as the returned air which will be at the top of the refrigerator compartment becomes cool, it will gradually

descend to the bottom of the refrigerator compartment and will again ascend up the vertical passage ways to the different compartments; and by the system of continuous circulation of cool air through the compartments perfect refrigeration will be attained.

The inverted channel members 41 and 58 having the openings on the side walls thereof, adjacent the return horizontal passage ways in the separate compartments will have a tendency to increase the return current of air out through the discharge openings located adjacent the top of the refrigerator compartments which will aid the circulation of air through the different compartments.

The trays 44 and 60 which serve as containers for food stuffs, and also answer for top walls of the passage ways in the compartments, are loosely mounted on the rest 20 strips 43. The cooled temperature from the horizontal passageway will be radiated through the trays to the foodstuffs contained thereon, and the trays can be readily removed for the purpose of cleaning them, 25 and when so removed the horizontal passage ways are accessible, so that this improved show case counter can be kept in a sanitary condition.

This improved method of circulating the air will prevent foul atmospheric conditions in a device of this character, and food stuffs can be kept in a much more clean, cool and sanitary condition than heretofore; and as aforesaid in using this improvement in 35 connection with a combined show case and dining counter, customers can be assured of getting eatables in a clean and sanitary condition.

Furthermore in combining this improved serving counter and refrigerator as described, quicker service can be had, and a server will not have to be continually going back to the refrigerator or ice box now in use for perishable food stuffs, as this improved counter and show case is designed to contain such food stuffs.

Referring to Fig. 9, it is readily seen how this improved device can be applied to a show case having the front, top, and ends 50 entirely of glass with the vacuum chamber located therein, which could be very well adapted for butchers and the like where their goods can be in sight to the customers and do not have to be brought out of this improved refrigerator and show case until called for; which will eliminate the too frequent handling of meats, as is now carried on with different meats lying around on counters and butcher's blocks; and are also 55 exposed to the foul conditions of the surrounding atmosphere.

In order to be able to cut off the refrigerating air supply from any one of the compartments, a slide damper 63 such as shown 60 adjacent the horizontal passage way 34 in

the lower compartment 4 of Fig. 1, can be installed in each compartment.

What I claim is:

1. In a refrigerator counter, the combination of a series of compartments located 70 therein, with an air cooling section located in said counter, one of said compartments located above said cooling section, a passageway leading from said cooling section to each compartment, each of said passage- 75 ways forming means for conveying air from the bottom of said cooling section to said compartment, and means for discharging air from said compartments at a point adjacent the top of said cooling section. 80

2. In a refrigerator show case and counter, the combination of a series of compartments located therein, an air cooling section located in said counter, horizontal passageways located in said compartments, said 85 horizontal passageways traversing the length of said compartments on one side, and returning along the other side, said horizontal passageways connecting with said cooling section at the bottom and having discharg- 90 ing communication with said cooling section adjacent the top thereof.

3. In a refrigerator show case and counter, the combination of a series of compartments located therein, an air cooling section 95 located in said counter, horizontal passageways located in said compartments, removable trays located above said horizontal passageways and forming the top walls thereof, said horizontal passageways traversing the 100 length of said compartments on one side and returning along the other side, said horizontal passageways communicating with said cooling section at the bottom, and having a discharge communication with said 105 cooling section adjacent the top thereof.

4. In a refrigerator show case and counter the combination of a series of compartments located therein, an air cooling section located in said counter, horizontal return 110 passage ways located in said compartments communicating with the bottom of said cooling section, a hollow member located longitudinally in each horizontal passage way, a series of holes formed on one side of said 115 hollow member, the holes of said hollow members forming means of communication with the return side of each of said horizontal passage ways, the return side of said horizontal passage ways and hollow mem- 120 bers communicating with said cooling section adjacent the top thereof.

5. In a combined show case and refrigerator, the combination of a series of compartments, and an air cooling section, horizontally arranged air circulating passage- 125 ways located in said compartments, each of said passageways extending to and being in receiving communication with the lower end of said air cooling section and in dis- 130

charging communication with the upper end of said air cooling section.

6. In a combined show case and refrigerator, the combination of a series of compartments located therein, horizontal passageways located in said compartments, removable trays adapted to form the top wall of said passageways, said passageways being in

receiving communication with the lower end of an air cooling section and in discharging 10 communication with the upper end of said cooling section.

WILLIAM AMENDA.
